BUILDING CONSTRUCTION

Frederick M. Venzie, Philadelphia, Pa., assignor
to National Gypsum Company, Buffalo, N. Y.,
a corporation of Delaware

Application April 28, 1933, Serial No. 668,317

6 Claims. (Cl. 72—118)

My invention relates to building constructions and more particularly to a novel form of wall surfacing material and method of making the same, and constitutes a continuation in part of 5 the invention disclosed in my co-pending application Serial No. 663,916, filed April 1, 1933.

The invention disclosed in my co-pending application above referred to contemplates the insertion in slots formed in wall surfacing units of 10 metallic grooves or slideways and clip engaging means adjustably held within such grooves. Since making that invention I have found that the cost of making recesses in the units is out of proportion to the benefits derived therefrom 15 and I have perfected a method of forming such wall boards which decreases the cost to an extent where they are readily saleable.

My present invention contemplates the insertion in the surfacing units at the time of their 20 formation of metallic reinforcements forming grooves or slideways, and, further, contemplates the use of units so formed as the surfacing material for walls whereby the units may be readily erected without the penetration through the 25 joints between adjacent panels of supporting or holding means. The invention also includes a novel wall formed of such units and novel means for connecting the units to a support.

An object of my invention is to provide a novel 30 method of forming panels of the type described whereby the cost of making the same is materially reduced over that heretofore known.

Another object of my invention is to provide a method of making a surfacing unit in which 35 a metallic reinforcement forming a groove is inserted in the panel at the time of its formation.

A further object of my invention is to provide a novel wall structure including panels made by 40 the above suggested method.

Yet another object of my invention is to provide a novel means of attaching a unit of the type described to a supporting structure.

Other objects and advantages of my invention 45 will be apparent from the following specification, claims, and from the drawing in which:

Fig. 1 is a vertical rear elevation of a wall embodying my invention with parts broken away to show the structure therebehind;

50 Fig. 2 is a vertical sectional view on an enlarged scale taken on the line 2—2 of Fig. 1;

Fig. 3 is a horizontal sectional view taken on the line 3—3 of Fig. 1;

55 Fig. 4 is a detailed perspective view of the hook; Fig. 5 is an enlarged perspective view of the

socket into which the hook illustrated in Fig. 4 fits and which is adapted for connection to a support;

Fig. 6 is a detail perspective view of a clip adapted to hold the socket illustrated in Fig. 5 and connect the same to a channel member;

Fig. 7 is a vertical section through the plaster board panel embodying my invention; and

Fig. 8 is a diagrammatic view illustrating the method of forming the plaster board panel.

Referring now particularly to Figs. 1 to 3, my invention contemplates the use of metallic channel members 10 functioning as risers to which may be connected clips 11 having a transverse bar 11a (Fig. 6) at the ends of which extend at 15 right angles thereto and in parallelism fingers 11b adapted to be bent around the channel member 10 and hold the transverse bar 11a thereagainst. Additionally, when desired the clips may also be attached to the risers by rivets or 20 bolts passing through the hole 11c. In the same vertical planes with the fingers 11b but on the opposite side of the transverse bar 11a extend fingers 11d, each of which may be bent upwardly at their lower ends to form a socket 11e as 25 shown on the left of Fig. 6, left straight as shown on the right side of that figure or combined as shown. Where the socket is used the upper end of the fingers 11d may be cut to form a tab 11f which may be bent over to hold in place the 30 member seated in the socket 11e.

Clip 11 may support in its socket 11e a member 12 illustrated in detail in Fig. 5, comprising a socket 12a formed in the lower end thereof, the outer face of which seats in the socket 11e of the clip 11, the inner surface of which is adapted to engage a hook 13, and the upper edge of which is adapted to be engaged by the tab 11f. Optionally the member 12, if wood studding is used, may be attached thereto by suitable elements 35 such as nails passing through the holes 12c and may be shortened as shown at 12d (Fig. 6) and engage the clip 11 with its upper hook shaped edge 12e. Where the member 12 is supported by the socket 11e the hook 12e may be eliminated or 40 flattened if desired.

The hook 13 comprises two parallel faces 13a and 13b, the latter of which engages the socket 12a in the member 12 and the former of which is engaged by a slideway in the surfacing unit, 50 the two faces being connected by an angular portion 13c. The face 13a of the hook 13 seats in a metallic slideway 14 formed in a unit 15 as illustrated in Fig. 2.

In the formation of panels suitable for surfac- 55

ing walls in various building constructions the normal procedure is to use compositions of various kinds of fluid or semi-fluid consistency which hardens into shape upon exposure to the atmosphere for a predetermined time. Occasionally such materials are also subjected to pressure at the time of their formation. Examples of such materials are "Transite", "Marbelite", or various types of plaster board, one of which will be described in detail for the purpose of illustrating my invention.

Plaster board, as is well known, is made by passing between two strips of paper 17 and 18 coming from rolls 19 and 20 a cementitious mixture indicated at 21 coming from the hopper 22 and thereafter passing the two strips of paper with the mixture therebetween between sizing rollers indicated at 24, after which the mixture is allowed to harden and the boards cut to shape. In accordance with my invention, upon one of the rolls of paper indicated at 19 I provide at suitably spaced intervals my metallic slideways 14 held in place against the paper of the roller by any suitable means such for instance as indicated in Figs. 7 and 8, by wire clips to the strip 17. In this way the slideways are caused to be embedded in the still plastic cementitious material as it is passed between the sizing rollers and the slideways made a homogeneous part of the plaster board. The slideways 14 preferably, in cross section, are in the shape of three connected truncated cones opened at the smaller ends, one of the open ends facing outwardly of the plaster board and two facing inwardly, whereby a tight interlock by the plaster upon the slideway is obtained.

In erecting boards so formed the mechanic by locking at the edges of the board can ascertain where the slideways are located and can slit the paper 17 covering the same with his finger nail or by any other suitable means. Obviously where materials differing from plaster board are used, that is, in those materials eliminating the paper covering, the metallic insert may be inserted in the plastic material prior to its hardening by hand at desired locations and the same result will be obtained whether pressure is thereafter applied to the composition or it is permitted to harden of its own accord.

Various modifications may be made in the

above described embodiment of my invention without departing from the spirit and scope thereof, as set forth in the following claims.

What is claimed is:

1. A surfacing unit for use in buildings comprising a hardened cementitious material having formed integrally therewith a metallic slide-way which is held in place by said material and a paper covering over said cementitious material and slideway. 5
2. A surfacing unit for use in buildings comprising a hardened plastic shape having formed integrally therewith a metallic element forming a groove adjacent one major surface of said shape and a paper covering over said groove. 10
3. A building construction comprising a support, a clip engaging said support, a socket carried by said clip, a hook engaging said socket, a wall surfacing unit, and means engaging said surfacing unit for slidably carrying said hook. 15
4. A building construction comprising a support, a connecting member, a metal clip carried by said support, said clip having fingers adapted to be bent about said support and other fingers adapted to carry said connecting member, a hook, said connecting member having a socket adapted to detachably engage said hook, and a metal slideway integrally connected with a non-metallic surfacing unit forming a seat for said hook. 20
5. A surfacing unit for building construction comprising a hardened cementitious material having a flexible covering on both sides thereof and a slideway formed integrally therewith, said slideway comprising a metallic element shaped as three connected dovetails, one of said dovetails being reversed with respect to the other two, said two dovetails being filled with said cementitious material, and means for connecting said slideway to said flexible covering. 25
6. A wall construction comprising studding, 40 plaster board panels positioned with one face toward said studding, horizontal slots in said face running lengthwise of said wall, a metal lining in said slots, a clip in movable relationship with said lining, and means engaging said clip and said studding for connecting the same and thereby maintaining said clip in fixed relationship with said lining and said panels in fixed relationship with said studding. 45
